(57) **CLAIM**

The ornamental design for a light, as shown and described.

DESCRIPTION

A first embodiment of the design is shown in FIG. 1 through FIG. 8:

FIG. 1 is a side and top perspective view of the new, original, and ornamental design of the light;

FIG. 2 is a side and bottom perspective view thereof;

FIG. 3 is a back elevation view thereof;

FIG. 4 is a front elevation view thereof;

FIG. 5 is a top plan view thereof;

FIG. 6 is a bottom plan view thereof;

FIG. 7 is an elevation view of the first side thereof, and FIG. 8 is an elevation view of the second side thereof.

A second embodiment of the design is shown in FIG. 9 through FIG. 16:

FIG. 9 is a side and top perspective view of the new, original, and ornamental design of the light;

FIG. 10 is a side and bottom perspective view thereof;

FIG. 11 is a back elevation view thereof;

FIG. 12 is a front elevation view thereof;

FIG. 13 is a top plan view thereof;

FIG. 14 is a bottom plan view thereof; and

FIG. 15 is an elevation view of the first side thereof; and, FIG. 16 is an elevation view of the second side thereof.

The broken lines shown on the drawings depict portions of the light that form no part of the claimed design.
